C. T. DANIEL.
CONTROLLING VALVE FOR A DRINKING FOUNTAIN.
APPLICATION FILED FEB. 21, 1916.

1,192,755.

Patented July 25, 1916.

UNITED STATES PATENT OFFICE.

CHARLES TODD DANIEL, OF OWENSBORO, KENTUCKY.

CONTROLLING-VALVE FOR A DRINKING-FOUNTAIN.

1,192,755.

Specification of Letters Patent. Patented July 25, 1916.

Application filed February 21, 1916. Serial No. 79,634.

To all whom it may concern:

Be it known that I, CHARLES T. DANIEL, a citizen of the United States, residing at Owensboro, in the county of Daviess, State 5 of Kentucky, have invented a new and useful Controlling-Valve for a Drinking-Fountain; and I do hereby declare the following to be a full, clear, and exact description of the invention, such as will enable others 10 skilled in the art to which it appertains to make and use the same.

This invention relates to an improved, simple and practical controlling valve, more especially adapted for use in connection 15 with drinking fountains, more particularly the kind that are adapted for use around school houses, churches, and the like, or other public places in rural districts, where there is no water pressure.

20 One of the features of the improved valve is the provision of means for taking up the wear upon the contacting ground seating surfaces.

25 Another feature of the valve is the provision of spring means between the valve casing and the operating handle of the valve, to return the valve to its initial position, there being limiting means to limit the valve in its open position.

30 In practical fields the details of construction may necessitate alterations, falling within the scope of what is claimed.

The invention comprises further features and combination of parts, as hereinafter set 35 forth, shown in the drawings and claimed.

In the drawings: Figure 1 is a vertical sectional view, showing parts in elevation, of the drinking fountain. Fig. 2 is an enlarged detail vertical sectional view through 40 the controlling valve. Fig. 3 is a sectional view on line 3—3 of Fig. 2. Fig. 4 is a sectional view on line 4—4 of Fig. 2.

Referring more especially to the drawings, 1 designates the wall of any suitable 45 structure, such as the schoolhouse, church or the like of a rural district. A water cooler or tank 2 is supported from the wall by the member 3, and is provided with a closure 4, and which tank or cooler may also hold the ice, as well as the drinking water. Extending from the lower end of the tank or cooler is a pipe or tube 5, which extends, through the flooring of the structure, and is connected as shown to the auxiliary tank

7, which is buried or sunken in the ground 55 under the flooring of the structure, in order to maintain the water cool in the summer-time, provided ice is not used in the tank 2. Also connected to the tank 7 is an outlet pipe 8, the lower extremity of which almost 60 reaches the bottom of the tank 7. The pipe or tube 7^a is threaded into the extension of the controlling valve casing 9, as shown at 10. Another section 11 of tube or pipe is threaded into the opposite extension 12 of 65 the controlling valve casing, as shown at 13, and which section 11 extends through the drain or overflow basin 14 of the drinking fountain, and is provided with an outlet nozzle 15, designed to have a contracted outlet opening, in order to cause a fine stream of water to emanate or leave the same. This fine stream elevates a short distance beyond the extremity of the nozzle, say for instance, about two inches, more or less, and then 70 overflows into the basin 14, which is secured to the wall 1 or other suitable support by the supporting means 16. A drain pipe 17 extends from the bottom of the basin, and passes through the wall of the structure, to 75 carry off the waste water. A cylindrical valve 18 is ground to fit the casing 9, and is provided with an annular recess 19. The valve 18 is provided with a transverse opening 20, which when the valve is in the position shown in Figs. 2 and 3, extends transversely. However, when the valve 18 is rotated partially, say for instance, quarter of a revolution, the opening 20 will register 80 with the passages 21 of the upper and lower 85 movable valve seat members 22, which are arranged in the opposite extensions of the casing 9. The valve seats 23 of these seat members are suitably ground to properly conform and engage the periphery of the 90 valve 18.

Interposed between the seat members 22 and the adjacent extremities (which are threaded into the opposite extensions of the casing 9) of the pipes or tubing 7^a and 11 100 are nipples 24. It is to be noted that when the valve seats 23 of said member 22 become worn, the pipes or tubes 7^a and 11 may be disconnected from the extensions of the valve casing 9, after which the nipples 24 105 may be adjusted by a spanner wrench or the like, so as to force the members 22 closer in contact with the valve 18, that is, closer in

contact with its seat, which is the bottom of the annular recess 19, thereby not only providing the proper contact between the valve and the members 22, but also holding the valve 18 in the casing 9 against axial movement of the valve. An annular collar 25 is secured by a screw 26 upon the reduced end 27 of the valve 18, and is provided with a handle or lever 28. A coil spring 29 is mounted upon the valve 18, and has one end secured to one end of the casing 9, and the other end to the collar 25, thereby acting to normally hold the opening 20 out of alignment with the passages 21 of the members 22, and the lug 30 normally in contact with the upper member 22. To open the valve, or in other words, to arrange the opening 20 in registration with the passages through the tubing 7^a and 11 and the members 22, 10 manual pressure is applied to the lever 28, against the action of the spring 29, thereby allowing the water to emanate from the nozzle 15. A drain pipe 31 is coupled at 32 to the tubing 7^a, and is provided with a valve 33, adapted to be opened, to drain off the system below the controlling valve. When drinking from the fountain, the object is to place the mouth over the stream of water, after opening the controlling valve, without 20 contacting with the nozzle 15, thereby insuring sanitation.

The invention having been set forth, what is claimed as new and useful is:

1. In a water distributing system, a controlling valve comprising a casing having oppositely arranged passages, a cylindrical valve member provided with a transverse opening to abnormally register with said passages and having an annular recess adjoining the opening, diametrically opposite valve seat members extending into the annular recess, a lever on the valve, and spring means on the valve connecting between the casing and the lever, to hold the opening normally out of register with the opposite passages.

2. In a water distributing system, a controlling valve comprising a casing having oppositely arranged passages, a cylindrical valve member provided with a transverse opening to abnormally register with said passages and having an annular recess adjoining the opening, diametrically opposite valve seat members extending into the annular recess, a lever on the valve, and spring means on the valve connecting between the casing and the lever, to hold the opening normally out of register with the opposite passages, and means for adjusting the valve seat members into the annular recess to compensate for the wear upon the contacting surfaces.

3. In a water distributing system for a controlling valve comprising a casing having diametrically opposite extensions, a cylindrical valve in said casing provided with an annular recess and a transverse opening adjoining the recess, said recess constituting a seat, valve seat members in the diametrically opposite extensions contacting diametrically with the seat of the recess acting to hold the valve member in the casing against axial movement, nipples in said extensions for adjusting the valve seat members toward the seat of the recess, spring tensioning means for the valve member, and a lever on the valve for rocking the same to throw its transverse opening in registration with the passages against the action of the spring means.

In testimony whereof I have signed my name to this specification in the presence of two subscribing witnesses.

CHARLES TODD DANIEL.
